UNITED STATES PATENT OFFICE.

FRIEDRICH C. ERNST, OF NEW YORK, N. Y.

UMBRELLA-RIB-TIP RETAINER.

1,405,402.

Specification of Letters Patent.

Patented Feb. 7, 1922.

Application filed May 4, 1920. Serial No. 378,854.

To all whom it may concern:

Be it known that I, FRIEDRICH C. ERNST, a citizen of the United States, and a resident of New York, in the county of Kings and State of New York, have invented certain new and useful Improvements in Umbrella-Rib-Tip Retainers, of which the following is a specification.

The present invention relates to umbrella rib-tip retainers, or in other words to means for holding the free ends of the ribs in position when the umbrella is closed. The invention pertains more particularly to that class of rib-tip retainers which is described in U. S. Letters Patent No. 1,144,182, granted to me on June 22, 1915. In this Letters Patent a device is described, comprising a sleeve having a longitudinal slot and two depressions at points diametrically opposite the said slot, one of said depressions being disposed near to the lower end and the other one near to the upper end of said sleeve. Upon the said sleeve is slidably disposed a cup having a cylindrical portion provided with a rib seated in said slot, whereby said cup is prevented from rotating in relation to said sleeve. The cylindrical portion of said cup has furthermore a projection adapted to enter the depressions in said sleeve, whereby said cup is held locked both in its upper and lower positions.

The main object of the present invention is to improve the device described in the said Letters Patent, mainly by simplifying the construction of both the sleeve and cup, thereby rendering the device capable of manufacture on a commercial scale, that is to say making it so convenient to produce so that it can be sold at a reasonable cost.

With these and other objects in view, which will more fully appear as the nature of the invention is better understood, the same consists in the combination, arrangement and construction of parts hereinafter described, pointed out in the appended claim and illustrated in the accompanying drawings, it being understood that many changes may be made in the size and proportion of the several parts and details of construction within the scope of the appended claim without departing from the spirit or sacrificing any of the advantages of the invention.

One of the many possible embodiments of

the invention is illustrated in the accompanying drawings, in which:—

Figure 1 is an elevation of an umbrella handle and part of the umbrella having the invention applied thereto; Figs. 2 to 4, inclusive, are sections taken, in their order, on lines 2—2, 3—3 and 4—4 of Fig. 1, on a larger scale; Fig 5 is a perspective view, on a larger scale, of a sleeve forming one of the elements of the retainer; and Fig. 6 is a transverse section taken through a portion of a cup forming the other element of the retainer.

In the drawings, the numeral 10 indicates an umbrella stick, to which is attached a handle 11 of any suitable shape. The inner end of this handle has a reduced portion 12, over which is drawn a sleeve 13. This sleeve may be held in position upon the handle in any suitable manner. The sleeve is provided with a longitudinal slot 15, having an enlargement 16 adjacent one of its ends, and an enlargement 17 adjacent the other end thereof.

On the sleeve is slidably disposed a retaining cup 18, having a cylindrical portion 19, on the inner face of which is formed a longitudinal rib 20, said rib being shorter than and seated in the slot 15. This rib is provided at its middle portion with sidewardly extending projections 21, that are adapted to enter either one of the enlargements of the slot 15.

The operation of this device is as follows:—The sliding motion of the cup upon the sleeve is limited by the rib 20 and slot 15 co-operating therewith. When the edge 20' of the rib 20 abuts against the end edge 15' of the slot 15, the projections 21 are seated in the enlargement 16 of the said slot, and, when the edge 20" of the rib abuts against the end edge 15" of the slot, the projections 21 are seated in the enlargement 17 of the slot. In both cases, the cup will be firmly held in these extreme positions, the cup being made of thin sheet metal and being thus somewhat resilient, so that the projections 21 thereon will spring in place when they are brought into registering position with either one of the enlargements of the slot in the sleeve. At the same time, some force will be required to unseat the projections 21 from the enlargements of the slot, so that the cup is firmly held

against accidental or unintentional operation. The coacting rib 20 and slot 15 of the cup and in the sleeve, respectively, prevent a turning movement of the said cup relative 5 to the sleeve.

When the parts are in the positions shown in Fig. 1 of the drawings and it is intended to open the umbrella, the cup is slid away from the tips, whereby its projections 21 10 are unseated from the enlargement 16 of the slot in the sleeve and seated in enlargement 17 therein. The umbrella can then be opened in the usual manner, inasmuch as the cup does not engage with the rib-tips. When the 15 umbrella is closed and it is intended to keep it in closed position, the cup is slid toward the tips, whereby its projections 21 are seated in the slot enlargement 16.

From the foregoing it appears that the 20 rib 20 and its projections 21 on the cup 18, in co-operation with the slot 15 in the sleeve, prevent a rotation and limit the sliding

movement of the cup upon the sleeve, and also hold the cup in either one of its extreme positions.

What I claim is:—

An umbrella rib-tip retainer, comprising a sleeve having a longitudinal slot provided with enlargements adjacent its ends, and a cup having a cylindrical portion slidably disposed upon said sleeve, said cylindrical portion having a rib seated in said slot whereby said cup is prevented from rotation in relation to said sleeve, the middle portion of said rib being provided with side- 30 wardly extending projections adapted to enter the enlargements of said slot, whereby said cup is held locked in both of its extreme positions.

Signed at New York, in the county of 40 Kings, and State of New York, this 3rd day of May, A. D. 1919.

FRIEDRICH C. ERNST.
